DESIGN FOR A SANDAL

Alan N. Steyne, Washington, D. C.; Eugene Untermyer and Elise S. Untermyer, executors of said Alan N. Steyne, deceased, assignors to Elise S. Untermyer, New York, N. Y.

Application May 20, 1946, Serial No. 129,878

Term of patent 14 years

(Cl. D7—7)

To all whom it may concern:

Be it known that I, Alan N. Steyne, a citizen of the United States, residing at Washington, District of Columbia, have invented a new, original, and ornamental Design for Sandals, of which the following is a specification, reference being had to the accompanying drawing, forming a part thereof.

I claim:

The ornamental design for a sandal, substantially as shown.

ALAN N. STEYNE.
